Primary Examiner — Nicole C Shiflet*Assistant Examiner* — Danielle Nichole Bowly(74) *Attorney, Agent, or Firm* — Sunstein LLP(57) **CLAIM**

The ornamental design for a laparoscopy simulator, as shown and described.

DESCRIPTION

FIG. 1 is a rear perspective view of the laparoscopy simulator;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

Those portions of the drawings indicated in broken lines form no part of the claimed design.
